(57) **CLAIM**

The ornamental design for a display screen with transitional
graphical user interface, as shown and described.

DESCRIPTION

FIG. 1 is a view of a first image of a sequence for a display
screen with transitional graphical user interface, according
to the embodiment of the claimed design;

FIG. 2 is a view of a second image of the sequence thereof;
and,

FIG. 3 is a view of a third image of the sequence thereof.
FIGS. 1-3 illustrate an embodiment of a display screen with
transitional graphical user interface having the claimed
design. The process or period in which one image transitions
to another image forms no part of the claimed design.

The dash-dash broken lines in the drawings are included for
the purpose of illustrating the unclaimed environment of the
design (e.g., a mobile/electronic device), or the unclaimed
article of manufacture (e.g., the display screen/panel), such
as the edge of the device comprising the display screen,
physical buttons on the outer edge of the device, virtual or
physical items on the display screen, or portions of the
graphical user interface. The dash-dot-dash broken lines in
the drawings are included for the purpose of illustrating the
unclaimed article of manufacture, such as the edge of the
display screen. The dash-dash broken lines and dash-dot-
dash broken lines form no part of the claimed design.

1 Claim, 3 Drawing Sheets
